(57) **CLAIM**

The ornamental design for a propane tank cover/carryer, as shown and described.

DESCRIPTION

FIG. 1 is a front perspective view of the propane tank cover/carryer showing my new design;

FIG. 2 is a right side elevational view thereof;

FIG. 3 is a front elevational view thereof;

FIG. 4 is a top plan view thereof;

FIG. 5 is a bottom plan view thereof;

FIG. 6 is a left side elevational view thereof; and,

FIG. 7 is a rear elevational view thereof.

The short broken lines shown in FIGS. 1-7 represent conventional stitching.

The long broken lines shown in FIG. 1 depict environmental structure and form no part of the claimed design.
